UNITED STATES PATENT OFFICE.

EDWARD FOSTER CLARK, OF NORTH ATTLEBORO, MASSACHUSETTS, ASSIGNOR TO W. G. CLARK & CO., INC., OF NORTH ATTLEBORO, MASSACHUSETTS, A CORPORATION OF MASSACHUSETTS.

SEPARABLE CUFF BUTTON.

Application filed April 17, 1922. Serial No. 553,446.

To all whom it may concern:

Be it known that I, EDWARD FOSTER CLARK, a citizen of the United States, residing at North Attleboro, in the county of 5 Bristol and State of Massachusetts, have invented certain new and useful Improvements in Separable Cuff Buttons, of which the following is a specification.

My invention is an improved separable 10 cuff button, or the like, my object being to produce such a device from stampings with a minimum use of soldered joints; a further object is to produce such a device at a low price and in a way to permit the use of low 15 cost labor in assembling and making the same and withal to produce a separable button or link that will be easy to connect or disconnect and when connected will be firm and stable.

20 In the drawings:

Figure 1 is a perspective view of part of the female element of the link;

Figure 2 is a perspective of a spring holder plate;

25 Figure 3 is the split ring spring;

Figure 4 is a side elevation of Figure 1;

Figure 5 is a perspective of the male element of the link;

Figure 6 is a longitudinal sectional elevation on an enlarged scale, of the spring element, assembled; and

Figure 7 is a similar view of the link assembled.

My separable cuff button or link, is designed to be used by inserting one part of each link in a button hole in one side of the cuff and then connecting the two parts of the link to hold the cuff closed.

As shown in the drawings the female 40 member of the link is made up of a plate, 1, which upon its outer surface, may be suitably ornamented. A standard or pin, 2, rises from plate 1 and carries at its upper end a cup, 3. Two spring holding plates, 4, 45 are provided, each bearing a recess 4^a at its center and a perforation 4^b and there is also a split ring spring 5. To assemble these parts, the spring ring is laid in the recess 4^a of a plate 4, where it surrounds the perfora-

tion 4^b. The other plate 4 is then applied, 50 the split ring resting in the recesses 4^a of both plates 4. The plate and spring assembly is then placed in the cup 3, the hollow 3^a of the cup being beneath the perforation 4^b, and the edges of the cup are then turned to connect the parts. 55

The male member of the link is made up of a plate A which upon its outer surface may be suitably ornamented. A pin B rises from plate A, the pin having a spherical 60 head B' and preferably a neck B². Below the neck B², fixed to the pin B is a plate C, close to the neck B² and parallel with plate A. I prefer to form a neck B² in the pin B, but this is not essential, as engagement 65 will be effected by the split ring 5 passing in behind the head B.

In operation, one member of the link having been applied to each side of the cuff, by passing the cup 3 and the plate C through 70 a button hole on each side of the cuff, the spherical head B' is passed through the apertures 4^b, spreading the spring ring 5, and into the hollow 3^a of the cup. The spring ring closes behind the head B' into the neck 75 B² and the plate C abuts the outer plate 4 of the female member stopping the male member with the short neck B² in position for split ring 5 to embrace it. Plate C it will be observed is identical with plates 4, 80 except that the recess C' is slightly larger than the recess 4^a of plates 4, and large enough in fact to receive the projection formed on the outer side of plate 4 by recess 4^a. The parts are so proportioned that 85 the split ring holds the pin B against longitudinal movement, while plates 4 and C abutting and interlocking at C' prevent any rocking. The two parts may be separated by a forcible pull, which will cause head B' 90 to spread split ring 5.

I claim:

1. The separable button above described, comprising a female member, made up of a plate, carrying a cup; a pair of recessed 95 plates, secured in the open end of the cup; a split spring ring between the plates, in the recess and a male member, made up of a

plate, carrying a pin having a wedging head, and a stop plate, substantially as described.

2. The separable button above described, comprising a female member, made up of a plate, carrying a cup; a pair of recessed plates secured in the open end of the cup; a split spring ring between the plates, in the

recess and a male member, made up of a plate, carrying a pin having a spherical head, a neck in the pin between the head and a stop plate, substantially as described.

Signed at North Attleboro, Massachusetts, this 13th day of April, 1922.

EDWARD FOSTER CLARK.
